NECKTIE CONSTRUCTION

William Mayer, New York, N. Y.

Application August 12, 1935, Serial No. 35,747

3 Claims. (Cl. 2—155)

My present invention relates generally to neckwear, and has particular reference to an improved type of adjustable neckband.

It is a general object of my invention to provide an improved adjustable necktie of the general character illustrated in United States Letters Patent No. 2,003,359, issued June 4, 1935. This type of necktie has a neckband portion whose effective length is adjustable by doubling a portion back upon itself and by providing at its end a male fastening element which is adapted to engage with a selected one of a series of openings or perforations in the neckband.

A more specific object of the present invention includes the provision of an improved assembly of parts whereby the tie is of enhanced attractive appearance, more compact in nature, easier to pass through or around a collar or neckband, and of a simplified structural nature which permits the tie to be manufactured at very small expense.

I have found that the manufacture of this general type of necktie can be simplified and improved by making use of a tubular woven fabric which is completely devoid of seams and which, when flattened, provides a staunch and highly efficient band within which the perforations hereinbefore mentioned may be provided.

In one embodiment of the present invention, the construction is similar to that of the aforementioned patent in that it permits the production of a tie by the usual and customary steps, and involves the mere additional application to the finished tie of a specially constructed band composed of flattened tubular-woven fabric.

In another embodiment, the band is made to constitute part of the tie construction itself, by constructing the inner ply of the neckband of shorter length than the outer ply and using the band as a continuation of the inner ply.

One of the advantages achieved by the present invention lies in the fact that the strength and durability of the resultant article are unusually good, and that the relatively delicate tie material is left intact and unimpaired, and adequately protected at all times, all stresses and strains being directed to, and taken up by, the specially constructed band of the present invention.

In the preferred embodiment, the tie includes a neckband portion which consists of inner and outer plies of material. These plies have their edges doubled inwards and stitched together, so as to form a relatively thick margin of at least four plies. The additional band of tubular-woven fabric is purposely narrower than the neckband portion and lies in its entirety within

the medial area between said margins. The added band is stitched at its edges to the outside of the inner ply of tie material; the stitches extend only through the inner ply; and the band has longitudinal edges which are virtually "selvaged"; and no special provision need be made to avoid raveling.

The present added band has a predetermined series of perforation which are arranged in longitudinally spaced relation. These perforations may take the form of circular openings, or they may be longitudinal slits, like button holes. They may extend through both plies of the tubular-woven band, or only through the outer ply. Where they extend through both plies, means are provided for interengaging the margins of the perforations so that the two plies are permanently secured to each other. In the completed structure, the midportion of the neckband has a thickness no greater than that of the margins, and the construction is characterized by a minimum of stitches which might impair the attractive appearance of the tie.

A particular feature of my invention lies in employing a tubular-woven band whose opposite external surfaces have distinguishable hues inherent in the weave of the band. One side may, for example, be white or substantially white, while the other side is black or substantially black. This permits a stock of the band material to be employed, at will, for white dress ties or for ties of darker hue merely by disposing the selected surface of the band outwardly when it is associated with the tie construction.

Among the advantages of the tubular woven fabric which I employ, as compared with the assembly illustrated in the aforementioned patent, are the absence of a selvaging problem, the avoidance of the necessity for care in properly centering a separate reinforcement band to a separate strip, and the provision of a two-ply assembly without requiring separate stitching operations or the handling of more than one piece of material.

I achieve the foregoing objects, and such other objects as may hereinafter appear or be pointed out, in the manner illustratively exemplified in the accompanying drawings, wherein—

Figure 1 is a perspective view of a tie of the ready-made variety, embodying the features of my present invention;

Figure 2 is a perspective view of a piece of the tubular-woven fabric which I employ for the perforated band;

Figure 3 is an enlarged cross-sectional view

taken substantially along the line 8—8 of Figure 1;

Figure 4 is a view similar to Figure 3, illustrating a modification;

5 Figure 5 is a view similar to Figures 3 and 4, illustrating a further modification;

Figure 6 is a perspective view showing the manner in which the invention may be applied with equal facility to the type of tie that is not ready-made;

10 Figure 7 is a perspective view showing the manner in which the invention is adapted to a four-in-hand type of tie;

Figure 8 is a view similar to Figure 1, illustrating a modified embodiment;

15 Figure 9 is an enlarged cross-sectional view taken substantially along the line 9—9 of Figure 8;

Figure 10 is a cross-sectional view taken substantially along the line 10—10 of Figure 8;

20 Figure 11 is a view similar to Figure 10, illustrating a modification; and

Figure 12 is a view similar to Figures 10 and 11, illustrating a further modification.

25 The ready-made type of bow tie illustrated in Figure 1 embodies the bow 20 and the preformed knot 21. Extending in opposite directions from the rear of the knot 21 are the neckband portions 22 and 23. The neckband of the tie is adjustable 30 in length by providing a male fastening element 24 at the extremity of the portion 23, whereby this portion may be doubled back upon itself to engage the fastening element in any one of a series of perforations provided in a predetermined arrangement. A metallic loop 25 is slidably mounted on the neckband portion 23 and is adapted to be engaged at its midportion by a hook 26 that is carried at the extremity of the neckband portion 22.

40 The manner of applying the hook 26 and the fastening element 24 to the extremities of the neckband portions has not been illustrated in detail, because these particular portions of the structure have no bearing upon the present invention.

45 The present tie is made up of inner and outer plies 27 and 28 (see Figure 3) of relatively delicate and usually ornamented tie fabric; and in the finished construction the longitudinal edges of these plies are doubled inwards and stitched together, 50 as at 29, whereby a relatively thick margin of at least four plies is provided. To those skilled in the art, it will be obvious that this mode of stitching requires that the plies 27 and 28 be initially stitched together in back-to-back relationship 55 and thereafter turned inside-out.

In accordance with my present invention, an additional band 30 is stitched, as at 31, to the outside of the inner ply 27. The band 30 is purposely narrower than the neckband by an extent which 60 permits the stitches 31 to lie within the medial area between the thicker margins of the neckband.

In accordance with my present invention, the band 30 is a length of tubular-woven fabric which 65 is flattened into the condition shown in Figure 2. The manufacture of this band involves no longitudinal stitches to hold the two plies together, and as a result the longitudinal edges of the resultant flattened band are virtually "selvaged", with no 70 danger of any raveling.

It is possible in the manufacture of the band 30, to control the weaving in a manner whereby one surface (e. g., the surface 32) has a relatively light hue, while the opposite exterior surface (e. g., the surface 33) has a relatively dark 75

hue. These distinguishable hues are inherent in the weave of the tubular-woven band.

In accordance with my invention, the band 30 is provided, along a medial longitudinal line, with a series of longitudinally spaced perforations 34. 5 Where, as in Figure 1, the male fastening element 24 is in the form of a metallic or similar hook, it is preferable that the perforations 34 be substantially circular openings. In the preferred embodiment, the openings 34 extend 10 through both plies of the band 30, as shown in Figure 3, and in such an event the margins of the perforations 34 are interengaged by stitches, eyelets, or by threads inherent in the weave of the band itself. This interengagement holds the 15 band in flattened condition so that, while it is essentially tubular in character it is, in effect, a single flat band or element which has no tendency to reopen into tubular condition.

In constructing the tie, the tubular-woven band 20 30 is first provided with the openings 34, and it is then permanently secured to the tie itself by means of the stitches 31. During this assembly, the selected surface 32 or 33 is disposed outwardly. In the case of a tie of relatively dark 25 coloration, the relatively dark surface is disposed outwardly, and in the case of a lighter or white tie, the lighter or white surface of the band is disposed outwardly. Thereafter, the tie ply 27 is stitched, back to back, to the ply 28, and the assembly is finally turned inside-out.

Preferably, though not necessarily, the band 30 carries markings 35 arranged adjacent to the perforations, respectively, so as to designate neckband sizes, so that when the effective length of 35 the neckband is to be adjusted the fastening element 24 may be engaged with any selected perforation in accordance with the sizes enumerated on the band 30.

The efficient nature of the complete preferred 40 assembly is shown most clearly in Figure 3, wherein it will be observed that the tie is no thicker at its midportion than at its margin. This arises from the fact that there are a total of four thicknesses of material at the midportion, 45 and a total of four thicknesses at the margins. It is further to be observed that the stitches 31 extend only through the ply 27, whereby the outside of the tie is left completely smooth and unimpaired in appearance.

In Figure 4, I have illustrated the nature of a modified construction in which the perforations 36 are in the form of elongated longitudinal slits, serving as the equivalent of buttonholes. This construction is preferable when the male fastening element 37 is in the form of a button, as shown, for example, at 37, in Figure 5.

In Figure 4, the buttonhole slits 36 extend through both plies of the band 30, and in Figure 5 I have shown the possibility of providing these 60 slits, designated by the reference numeral 38, through only the outer ply of the band 30. One of the advantages of this construction lies in the fact that when the button 37 is in position, there are three thicknesses of material separating the 65 button from the outside surface of the tie; whereas, in Figure 4, there would be only two. In a case wherein the tie fabric is of relatively delicate material, the extra thickness overlying the button 37 is desirable in guarding the tie 70 fabric against wear, and also more effectively concealing from the exterior the fact that a button is being employed.

The construction of Figure 5 is not suitable where a hook (like that at 24 in Figure 1) is the 75

fastening element, because the engagement of a hook with only a single ply of material would have a tendency to tear the material. Bearing this in mind, the advantage of the construction 5 of Figure 3 will be more readily appreciated, inasmuch as the inner ply of the tubular band serves as the equivalent of the reinforcement band especially provided for this purpose in the construction of the aforementioned patent.

10 In Figure 6, I have shown the manner in which the invention is applied with equal facility to a tie that is not of the ready-made variety. In this case, the bow portions 39 and 40 are each provided with neckband portions 41 and 42 respectively. The portion 42 is permanently secured, as at 43, to a metallic elongated link through which the other neckband portion 41 slidably extends. At the extremity of the portion 41 I provide a male fastening element which 15 I have shown in the form of a button 44; and on the inside ply of the neckband portion 41 I attach the additional band of tubular-woven fabric which is designated in Figure 6 by the reference numeral 45. This band is applied, as hereinbefore described, and is provided with the slit perforations 46.

20 In Figure 7, the invention is shown applied to a ready made four-in-hand type of tie. Detailed description of this figure is not believed 25 to be necessary, since it will be obvious that the features hereinbefore described are exactly the same in Figure 7, except for the fact that the knot 47 is a four-in-hand type of knot instead of a bow knot.

30 It will also be understood that the invention is applicable to a regular four-in-hand tie, the tie in such a case being substantially identical with the tie illustrated in Figure 6, except that the ends 39 and 40 are considerably longer and 35 are shaped in the conventional four-in-hand manner.

35 In Figures 8-12 I have illustrated another manner in which a band of tubular-woven fabric may be associated with the tie construction to accomplish the same general objectives. In this case, the neckband portions 50 and 51 extend rearwardly, as before, the portion 50 having the hook 45 52 engageable with the loop 53, and the portion 51 carrying the male fastening element 54 at its 50 end.

55 The neckband portion 51 is composed of the inner and outer plies 55 and 56, the rear end terminating approximately at the line 58. The additional tubular band 59 is attached to the rear end of the ply 55 so as to form a continuation of the latter. This requires that the longitudinal edges of the band be stitched, as at 60, to the longitudinal edges of the outer ply 56. While this necessarily produces a margin of six-ply thickness, the construction may nevertheless be 60 deemed advantageous under certain circumstances, inasmuch as there is an absence, on the inner surface of the neckband, of an obviously added band, and of the extra stitches 31 (see 65 Figure 3).

65 In Figure 10, I have shown a series of perforations or openings 61 similar in nature to the perforations 34 of Figure 3. They extend through both plies of the tubular band 59, and they are 70 adapted to receive a male fastening element in the form of a hook, as shown at 54 in Figure 8.

In Figure 11, I have shown a series of perforations 62 in the form of elongated buttonhole slits, the construction being analogous to that of Figure 4.

75 In Figure 12, I have illustrated the manner in which the buttonhole perforation 63 may be made to extend only through the outer ply of the tubular band, this construction corresponding to that of Figure 5.

I have omitted additional figures corresponding 10 to Figures 6 and 7, but it will be readily understood that the mode of construction illustrated in Figures 8-12 may be applied with equal facility to ties which are not of the ready-made variety 15 and to ties of the four-in-hand type.

15 In general, it will be understood that changes in the details, herein described and illustrated for the purpose of explaining the nature of my invention, may be made by those skilled in the art without departing from the spirit and scope of the 20 invention as expressed in the appended claims. It is, therefore, intended that these details be interpreted as illustrative, and not in a limiting sense.

Having thus described my invention, and illustrated its use, what I claim as new and desire 25 to secure by Letters Patent is—

1. In an adjustable necktie having a neckband portion adapted to be doubled back upon itself, a male fastening element at the end of said portion, 30 and a band carried by the neckband portion on its inner surface and provided with longitudinally spaced perforations, whereby said fastening element may be engaged with any selected perforation to adjust the effective length of said neckband portion; said band comprising a length of 35 flattened tubular-woven fabric, and said perforations being longitudinal slits extending only through the exposed ply of said band.

2. In an adjustable necktie, a neckband portion adapted to be doubled back upon itself and comprising two plies of tie material having their longitudinal edges turned inwardly and stitched together, a male fastening element at the end of 45 said neckband portion, and a band carried by the 45 neckband portion on its inner surface and provided with longitudinally spaced perforations, whereby said fastening element may be engaged with any selected perforation to adjust the effective 50 length of said neckband portion; said band 50 comprising a length of flattened tubular-woven fabric narrower than the neckband portion and lying in its entirety within the medial area between said stitched edges.

3. In an adjustable necktie, a neckband portion adapted to be doubled back upon itself and comprising two plies of the tie material having their longitudinal edges turned inwardly and stitched together, the rear end of the inner ply terminating short of the rear end of the outer 60 ply, a male fastening element at the end of said neckband portion, and a band carried by the inner ply as a continuation of the latter and stitched at its longitudinal edges to the edges of 65 the outer ply, said band being provided with longitudinally spaced perforations, whereby said fastening element may be engaged with any selected perforation to adjust the effective length of said neckband portion, said band comprising a 70 length of flattened tubular-woven fabric.

WILLIAM MAYER.
